FOREIGN PATENT DOCUMENTS

CN 106848717 A 6/2017

Primary Examiner — Jennifer O King(74) *Attorney, Agent, or Firm* — Ming Chieh Chang; Wei Te Chung(57) **CLAIM**

The ornamental design for a protective cap, as shown and described.

DESCRIPTION

FIG. 1 is a perspective view of a Protective Cap showing our new design;

FIG. 2 is a front elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plane view thereof; and,

FIG. 8 is a perspective view thereof, shown in use.

The broken line showing of related parts is for the purpose of illustrating environmental structure and forms no part of the claimed design.

1 Claim, 8 Drawing Sheets(56)
